(57) **CLAIM**

The ornamental design for a vehicle roof rack for fishing ski, as shown and described.

DESCRIPTION

FIG. 1 is a front elevation view of a vehicle roof rack for fishing ski showing the new design;

FIG. 2 is a bottom plan view thereof;

FIG. 3 is a front, side, and top perspective view thereof; and, FIG. 4 is a top plan view thereof.

The sides of the vehicle roof rack for fishing ski are mirror images of each other.

The rear of the vehicle roof rack for fishing ski is a mirror image of the front shown in FIG. 1.
